UNITED STATES PATENT OFFICE.

ROWLAND ROBINSON HAZARD, OF NEW YORK, N. Y.

RAILWAY-CARRIAGE.

SPECIFICATION forming part of Letters Patent No. 368,947, dated August 30, 1887.

Application filed July 26, 1884. Serial No. 138,833. (No model.)

To all whom it may concern:

Be it known that I, ROWLAND ROBINSON HAZARD, a citizen of the United States, residing in the city, county, and State of New York, have invented a new and useful Improvement in Railway-Carriages, fully described and represented in the following specification and accompanying drawings, forming a part of the same.

10 One object that I have in view is the construction of such carriages in such manner and of such materials that, in the event of fracture from collision, the materials of which it is composed shall not become detached fragments, missiles, or projectiles calculated to inflict injury to passengers.

Another object is to reduce the resonance induced by the rapid passage of such carriages through a tunnel or confined space, and to 20 combine in a railway-carriage these tough and non-resonant characteristics.

I accomplish the above objects by the improved construction hereinafter described.

In the accompanying drawings, forming a 25 part hereof, Figures 1 and 2 represent horizontal cross-sections on line α of Fig. 3 of parts of the frame of the carriage constructed in accordance with my invention. Fig. 3 is a side elevation of a railway-carriage illustrating my 30 invention. Fig. 4 is a view of the compound non-resonant fabric, partly broken away to show its construction. Fig. 5 is a cross-section of Fig. 4.

In an underground, tubular, or viaduct 35 railway structure, resonance occasioned by the passage of trains constitutes a serious and under some conditions a prohibitory objection.

I have invented a non-resonant tunnel, tube, 40 or viaduct for which an application for Letters Patent has been filed. This invention is complementary to that, the carriage herein described being preferably used in said tunnel, tube, or viaduct. When a railway-car breaks 45 up in consequence of collision, the parts are detached, becoming flying missiles projected into contact with passengers or bystanders or under passing trains, and numerous fatal and other injuries are inflicted.

50 The frame of my carriage consists of sill, cornice, posts, floor and roof beams, and

braces, constituting a skeleton, (one method of construction being shown in the drawings,) which may be made in any form or arrangement of parts of mild steel or other suitable 55 strong, elastic, and tough metal. The vertical posts a , the horizontal beams $b d f$, and the floor-beams are constructed of angle-iron or steel, in order to secure the greatest possible strength and stiffness. The said posts and 60 beams are braced by the diagonal braces g . This skeleton frame-work, firmly bolted together as hereinafter described, is exceedingly strong and stiff, and is not liable to become impaired by the shocks to which railway-carriages are frequently subjected. This frame-work is covered on the outside and inside, or either, with an elastic, tough, non-resonant material, (indicated by C in the drawings,) 65 consisting of woven fabric, grating, lattice, or crimp of metal overlaid on one or both sides with flax, ootrum, esparto, asbestos, or any 70 suitable vegetable, or mineral fiber, with oxidized or solidified vegetable oil, rubber, gutta-percha, or equivalent material, formed into 75 panels, sheets, or plates by hydraulic or other pressure, and applied to said frame by clamping-bars, bolts, screws, or otherwise, to form the walls, floor, roofs, or either or any of them, substantially as shown.

Referring to Figs. 4 and 5 of the drawings, h designates the woven fabric or grating of metal, and i the fiber applied thereto. This fiber is treated with oil or equivalent material, as before described, and the whole is subjected to hydraulic or other pressure, so that 85 the fiber may become thoroughly united to the woven fabric of metal and the completed article constitute a compound fabric. This material fulfills all the conditions required by 90 my invention, but is not here claimed, but is claimed in another application filed July 26, 1884, Serial No. 138,857.

Wood, glass, and other material readily reduced to fragments by collision are preferably 95 omitted from carriages constructed in accordance with my invention.

For continuous tunnel service windows are omitted, and incandescence preferably provided as a means of lighting.

The term "non-fracturable" is used in the specification and claims in a relative sense,

and as properly applicable to any strong, elastic, and tough metal; and by the expression "compound fabric" is to be understood a fabric consisting of metal and fiber thoroughly united, as described.

I am aware that it has been proposed to construct the frame of a railway-car of thin sheets of metal riveted together like boiler-plates, and to cover the same on both sides ¹⁰ with rubber or gutta-percha; also, that the frame of a car has been constructed of interlacing metallic strips covered on the inside and outside with rubber or gutta-percha; also, that the frame of a car has been constructed ¹⁵ of horizontal bars of angle and vertical posts of grooved iron, and that a lattice-work of iron wire has been secured to such frame, said lattice-work being covered with felt and said felt covered with oil-cloth or painted canvas, ²⁰ as set forth in English Patent No. 2,779 of 1856, and to these several constructions I lay no claim; but

What I claim is—

1. A railway-carriage consisting of a skeleton ²⁵ ton frame-work of non-fracturable material

covered by a compound fabric composed of woven metal combined with a suitable fiber and a vegetable oil or equivalent, substantially as described.

2. A railway-carriage consisting of a skeleton frame-work of angle-iron or steel covered by a compound fabric composed of woven metal combined with a suitable fiber and a vegetable oil or equivalent, substantially as described. ³⁰

3. A passenger-railway carriage consisting of vertical posts, horizontal beams, and diagonal braces of iron or steel, having its sides unprovided with windows, and covered by a compound fabric composed of woven metal ⁴⁰ combined with a suitable fiber and a vegetable oil or equivalent, substantially as described.

In testimony whereof I have hereunto set my hand in the presence of two subscribing witnesses.

ROWLAND ROBINSON HAZARD.
